UNITED STATES PATENT OFFICE.

EDWARD E. HINRICHSEN, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,305,981.

Specification of Letters Patent. Patented June 3, 1919.

Application filed May 22, 1917. Serial No. 170,307.

To all whom it may concern:

Be it known that I, EDWARD E. HINRICHSEN, a citizen of the United States, residing at New York, in the county of New York and State of New York, have invented certain new and useful Improvements in Telephone Systems, of which the following is a full, clear, concise, and exact description.

10 This invention relates to telephone systems, and more particularly to such systems of the measured service type.

The object of this invention is to provide a system of this character in which a message register or service meter will be positive in operation and will not be subject to such marginal operating conditions as have been experienced with message registers heretofore used, and in which the operation 20 of the register will not be affected by the variations in the other apparatus associated with the system in which the message register is included.

In accordance with a feature of this invention, an electromagnet associated with a telephone line is partially energized upon the connection of a link circuit with the line and is further energized upon the actuation of a switch associated with the link 30 circuit to cause the operation of a message register whose electromagnet is included in a local circuit controlled by the first mentioned electromagnet.

For a more complete understanding of this invention reference should be had to the following description taken in connection with the drawing, wherein is shown so much of a telephone system as is necessary for the proper understanding of this invention.

In the drawing there is shown a telephone line A extending from a subscriber's station to a central office at which is located a cord circuit for extending the telephone line A. There is shown in the drawing a line jack B in which another telephone line terminates. Associated with the line A is an ordinary line relay 5 controlling a line signal 6. There is also associated with the line A a cut-off relay 7 having two windings and which, when partially energized, attracts its left-hand armatures to disconnect the line relay 5 from the line and when fully or further energized attracts all of

its armatures causing, the energization of 55 an electromagnet 8 which, through its armature 9 and associated pawl 10 for engaging a ratchet wheel 11, actuates a message register M.

Subscriber A in initiating a call removes 60 the receiver from the switchhook, causing the energization of the line relay 5, which attracts its armature to light the line lamp 6. The operator observing the condition of this line lamp 6 inserts answering plug 15 65 into line jack 16, thereby causing the partial energization of the cut-off relay 7 over a circuit from battery through answering supervisory lamp 17, resistance 18, sleeve contacts of the answering plug 15 and line 70 jack 16, and the windings of cut-off relay 7 to ground. Since the receiver is off the switchhook, answering supervisory relay 19 will be energized, whereupon resistance 20 75 will be connected in parallel with the supervisory lamp 17, to efface the lamp. This partial energization of the cut-off relay 7 causes the attraction of its left-hand armatures 21 and 22, thereby disconnecting the line relay 5 from the line circuit and effacing the line lamp 6.

The operator may now actuate a listening key (not shown) to connect the operator's telephone set (also not shown) with the cord circuit. Upon being advised of 85 the number of the telephone line with which connection is desired, for example, the line connected with line jack B, the operator restores the listening key to normal position and inserts calling plug 25 into line jack 90 B. Calling supervisory lamp 28 is thereupon lighted. The subscriber connected with that line may be signaled in any desired manner. This called subscriber, in responding, causes the energization of calling supervisory relay 26, which connects resistance 27 in parallel with the calling supervisory lamp 28, thereby effacing the lamp. The effacement of this lamp indicates to the operator that the called subscriber has responded and is a signal that the call initiated by subscriber A may now be counted.

The operator counts the call by actuating 105 a message register key 30, thereby completing a circuit from a message register battery 31, which is of higher voltage than the ordinary central office battery, through the

winding of relay 32, contact of message register key 30, sleeve contacts of the answering plug 15 and line jack 16; and the windings of cut-off relay 7 to ground. Relay 32 is marginal and does not operate when in circuit with both windings of the cut-off relay, but does operate when included in circuit with the left-hand winding only. The completion of this circuit causes the further energization of cut-off relay 7, whereupon its right-hand armature 33 is attracted, completing an energizing circuit for the electromagnet 8, which now attracts its armature to operate the message register 15 M. Upon the attraction of the armature 9 by electromagnet 8 a contact is closed which establishes a short circuit for the right-hand winding of cut-off relay 7, thereby reducing the resistance in circuit with relay 32 and permitting the operation thereof. Relay 32 in operating completes a circuit for a lamp 34, which is lighted to indicate to the operator that the message register has operated. The operator may now 25 restore the key 30 to normal, thereby removing the message register battery 31 and relay 32 from the circuit. The lamp 34 is thereby effaced. Cut-off relay 7, however, does not release its armatures but maintains all three attracted. While the cut-off relay 7 will not attract its armature 33, when in circuit with the usual central office battery, when once this armature is attracted, it is maintained in position by current 30 from the usual central office battery only. The right-hand winding of cut-off relay 7 is of few turns compared to the left-hand winding, so that the reduction in number of turns caused by the short-circuiting of the 40 right-hand winding is compensated for by the resulting increase of current through the left-hand winding.

From this description it will be seen that by including the message register operating electromagnet in a local circuit the variations of resistance in other apparatus has less effect upon the operating margins of the message register magnet than when it is included in parallel or in series with the 50 cut-off relay as has heretofore been the practice. With no other apparatus in the circuit with the message register magnet the operating conditions for that magnet are very much less rigid than when other apparatus is included in the circuit.

What is claimed is:

1. A telephone system comprising a telephone line, a service meter therefor, a link circuit for extending the line; an electromagnet partially energized upon connection of the link circuit with the line; a switch actuated to further energize the electromagnet, a second electromagnet energized upon the further energization of the first to 60 actuate the service meter and a circuit estab-

lished upon the operation of the second electromagnet to maintain said first electromagnet energized.

2. A telephone system comprising a telephone line, a service meter therefor, a line signal for the line, a link circuit for extending the line, a cut-off relay partially energized upon connection of the link circuit with the line to disconnect the signal therefrom, a switch actuated to further energize the cut-off relay, an electromagnet energized upon the further energization of the cut-off relay to actuate the service meter and circuit connections rendered effective upon the operation of the electromagnet to maintain 75 the cut-off relay energized.

3. A telephone system comprising a telephone line, a line relay therefor, a line signal actuated upon the energization of the line relay, a service meter for the line, a link circuit for extending the line, a cut-off relay partially energized upon connection of the link circuit with the line to disconnect the line relay therefrom, a switch actuated to further energize the cut-off relay, 85 an electromagnet energized upon the further energization of the cut-off relay to actuate the service meter and means effective subsequent to the release of the switch to maintain the cut-off relay fully energized.

4. A telephone system comprising a telephone line, a service meter therefor, a link circuit for extending the line, a relay having a winding consisting of a plurality of turns, said relay being partially energized upon the connection of the link circuit with the line, a switch actuated to further energize the relay, an electromagnet energized upon the further energization of the relay to actuate the service meter; and a short circuit for a portion of the turns of the winding of said relay established upon the energization of the electromagnet to thereby maintain the relay energized upon the release of the switch.

5. A telephone system comprising a telephone line, a service meter therefor, a line signal for the line, a link circuit for extending the line, a cut-off relay having two windings and partially energized upon connection of the link circuit with the line to disconnect the signal therefrom, a switch actuated to further energize the cut-off relay, an electromagnet adapted when energized to actuate the service meter, an energizing circuit for the electromagnet including a contact of the cut-off relay completed upon the further energization thereof, and a short circuit for one winding of the cut-off relay established upon the energization 115 of the electromagnet.

6. A telephone exchange system comprising a telephone line, a service meter therefor, a link circuit for extending the line, a cut-off relay partially energized upon the 120

connection of the link circuit with the line, a switch actuated to further energize the cut-off relay, an electromagnet energized upon the further energization of the cut-off 5 relay to actuate the service meter, and means effective upon the operation of the electromagnet to maintain the cut-off relay operated.

7. A telephone exchange system comprising a telephone line, a service meter therefore, a link circuit for extending the line, a cut-off relay partially energized upon the connection of the link circuit with the line, a switch actuated to further energize the cut-off 10 relay, an electromagnet energized upon the further energization of the cut-off relay to actuate the service meter, a signal in the link circuit, and a short circuit for a portion of the winding of the cut-off relay for 15 controlling the signal.

8. A telephone exchange system comprising a telephone line, a service meter therefore, a link circuit for extending the line, a cut-off relay having two windings and partially energized upon the connection of the 20

link circuit with the line, a switch actuated to further energize the cut-off relay, a signal in the link circuit, an electromagnet energized upon the further energization of the cut-off relay to actuate the service meter, and a short circuit for one winding of the cut-off relay established upon the energization of the electromagnet for controlling the signal. 30

9. A telephone exchange system comprising a telephone line, a service meter therefore, a line relay, a link circuit for extending the line, a cut-off relay partially energized upon the connection of the link circuit with the line to disconnect the line relay therefrom, a switch actuated to further energize the cut-off relay, an electromagnet energized upon the further energization of the cut-off relay to actuate the service meter, a signal in the link circuit, and means operated upon 40 the energization of the electromagnet to cause the illumination of the signal. 45

In witness whereof, I hereunto subscribe my name this 18th day of May A. D., 1917.

EDWARD E. HINRICHSEN.
